[57] CLAIM

The ornamental design for an ice skate guard, substantially as shown and described.

DESCRIPTION

FIG. 1 is an upper front perspective view of the ice skate guard showing my new design.

FIG. 2 is a top plan view of the ice skate guard.

FIG. 3 is a rear view of the ice skate guard.

FIG. 4 is an upper front perspective view of a further embodiment of the ice skate guard.

FIG. 5 is a front view of the ice skate guard, and FIG. 6 is a bottom view of the ice skate guard shown in FIG. 1.

FIG. 1

FIG. 2

FIG. 3

FIG. 4

FIG. 5

FIG. 6
